UNITED STATES PATENT OFFICE.

FREDERICK EGGE AND CARL A. J. SJOBERG, OF BRIDGEPORT, CONNECTICUT;
SAID SJOBERG ASSIGNOR TO SAID EGGE.

ATTACHMENT FOR SEWING ON BUTTONS.

SPECIFICATION forming part of Letters Patent No. 268,470, dated December 5, 1882.

Application filed April 4, 1882. (No model.)

To all whom it may concern:

Be it known that we, FREDERICK EGGE and C. A. J. SJOBERG, citizens of the United States, residing at Bridgeport, in the county 5 of Fairfield and State of Connecticut, have invented certain new and useful Improvements in Attachments for Sewing on Buttons, of which the following is a specification, reference being had therein to the accompanying drawings.

10 Our invention relates to machines for sewing buttons on material of any flexible nature, and is intended as an attachment to be applied to an ordinary sewing-machine. It is designed more especially for sewing on buttons like the 15 ordinary shoe-button and others having an eye on the back. It may, however, be made equally useful for sewing on other kinds of buttons where there is a bar in or across the center of the button.

20 Our invention consists in the details of construction and elements of combination herein-after fully set forth, and then specifically designated in the claims.

In order that those skilled may more fully understand the construction and operation of our improved machine, we will proceed to describe the same in detail, referring by letters to the accompanying drawings, in which—

Figure 1 is a view in perspective of our improvement attached to an ordinary sewing-machine; Fig. 2, a central vertical longitudinal section of the same; Fig. 3, a top view, showing our improvement attached to a bed-plate and adapted to be secured to a sewing-machine; and Figs. 4 and 5, detail views of the switch-cam and upper or clamping plate, respectively.

Similar letters denote like parts in the several figures.

40 In machines of this description the fabric operated upon is uniformly and constantly shifted back and forth under the needle as the latter descends, or else it becomes necessary to use two needles or to oscillate the needle-bar. This former (or, as it is commonly called, “oscillatory”) motion is usually imparted by 45 means of a switch-cam arranged on the shaft of a sewing-machine, and a traveler in the channel of said cam.

Our device is secured to an oscillator, A, 50 such as described, and in the manner shown at Figs. 1 and 3, so that any motion imparted to the latter will likewise affect the former.

B B are spring-jaws, attached at their rear ends to the upper plate, C, of the clamping mechanism, the convergency of their front ends being limited by the pins a a. The front end of the clamping-plate C is provided with an opening, D, Figs. 3 and 5, to allow for the play of the needle as the oscillator moves to and fro, and a slight indentation, b, is made in the side of this opening, leaving stock enough below so as to provide a seat for the eye of the button when held between the jaws B.

The operation of our improved device for 65 sewing on buttons is as follows: The fabric or other material is first clamped in position by the action of the upper or clamping plate, C. As this plate descends the shoulders E E come in contact with the material or fabric, depressing the same out of the way, and thus greatly facilitating the insertion of the button between the jaws B. These shoulders are preferably made by forming the said upper plate, C, longer than the lower and turning over this 70 excess of stock at about right angles, although projections or pins may be fastened at the front end of said upper plate with like results. The work being properly clamped, an ordinary shoe-button is inserted between the jaws B in 75 such a manner that the eye will rest in position within the indentation or seat b. Power is now applied to the shaft of the sewing-machine and the oscillator A moves to and fro, thereby causing the needle to pierce alternately within and without the eye of the button. When a sufficient amount of thread has been stitched over said eye the clamp is raised, the work shifted, and the operation goes on as before. The connecting-threads between the several buttons may be readily cut without any danger of the fastenings pulling out. The jaws B are made at the outer end slightly bellied, as seen at Fig. 3, to conform to the shape and contour of the body of the 85 button, and the walls of such bellied portion slope downward and outward, so that the action of the jaws tends to facilitate the inser- 90 95

the button and to hold it against any upward movement.

What we claim as new, and desire to secure by Letters Patent, is—

1. In a machine for sewing on buttons, the spring-jaws B, fastened at their rear ends to the clamping-plate, the front ends converging, bellied, and inclined, substantially as set forth and described.

2. In a machine for sewing on buttons, the clamping-plate having an opening, D, and indentation or seat b at its outer end, in combination with the spring-jaws B, secured to said clamping-plate, substantially as described.

3. In a machine for sewing on buttons, the upper or clamping plate of the clamping mech-

anism, having its extreme outer ends turned over to form shoulders E, substantially as set forth.

4. In a machine for sewing on buttons, a 20 clamping-plate provided at its outer end with spring-jaws B, opening D, indentation or seat b, and shoulders E, substantially as hereinbefore set forth and described.

In testimony whereof we affix our signatures 25 in presence of two witnesses.

FREDERICK EGGE.

CARL A. J. SJOBERG.
